UNITED STATES PATENT OFFICE.

ROBERT W. LEE, OF BROOKLYN, NEW YORK, ASSIGNOR TO PYRENE MANUFACTURING COMPANY, A CORPORATION OF DELAWARE.

FIRE-EXTINGUISHER.

1,308,546.

Specification of Letters Patent. Patented July 1, 1919.

Application filed November 18, 1915. Serial No. 62,115.

To all whom it may concern:

Be it known that I, ROBERT W. LEE, a citizen of the United States, and resident of Brooklyn, county of Kings, city and State of New York, have invented certain new and useful Improvements in Fire-Extinguishers, of which the following is a specification.

This invention relates to a portable fire extinguisher of the type in which the liquid is expelled by manually operated means and has for an object the provision of a simple device which will enable the liquid to be discharged rapidly and in a constant stream.

For further comprehension of the invention reference will be had to the following description, taken in connection with the accompanying drawing, and to the appended claim, in which the novel features of the invention are more particularly set forth.

The figure in the drawing is a vertical sectional view of a device embodying the invention.

The extinguisher comprises a cylindrical receptacle 1, closed at opposite ends by the heads 2 and 3, the latter of which terminates in a nozzle portion 3' through which extends the discharge orifice 4.

Passing through the opposite head 2 is a hollow or tubular piston rod 5, having an operating handle 6 on its exterior end, a stuffing box 7 being provided on the head 2 to prevent leakage past the rod. This piston rod surrounds loosely a tube 8 screwed into the discharge orifice 4 and extending at its opposite end through the head 2. A plug or stopper 9 of suitable material is secured as by the pin 10, within the end of the piston rod 5 where it is joined to the handle 6, this stopper being adapted to engage and close the mouth of the tube 8 when the handle is depressed.

Communication between the body of the receptacle and the interior of the piston rod is provided by openings 11 in the wall of the latter, these passages being preferably located adjacent the piston.

This piston, as here shown, comprises a flange 12 rigid on the end of rod 5, while a pair of washers 13 and 14 are clamped between the flange 12 and a disk 15 by the screws 16. Washer 13 has an annular flange 13' engaging the interior wall of the recep-

tacle 1 while washer 14 has a similar flange 14' engaging the tube 8. Extending through the head 3 to the space between the latter and the piston is an air vent 17. Provision is made for filling the receptacle through an opening 19 in the head 2, which opening may be closed by the screw plug 20.

In the use of the device the handle is depressed to its normal position, as shown in the drawing, in which position the piston is adjacent the discharge end 2 and the receptacle filled, the piston constituting the bottom of the liquid holding portion of the receptacle.

When the liquid is to be discharged the handle is retracted and as the piston moves the liquid is forced through the openings 11 into the piston rod 5 and through the tube 8 to the discharge orifice 4, the initial movement of the handle raising the stopper 9 from the mouth of the tube 8.

It will be apparent that with the above described construction the device is ready for instant use and the liquid can be forced rapidly and in a steady stream from the receptacle and that the latter can be kept filled without any inconvenience from projecting parts.

I claim:

In a device of the class described, in combination, a cylindrical receptacle provided at one end with a discharge nozzle and an air inlet, said receptacle forming a piston cylinder and adapted to contain all of the liquid to be discharged, a piston positioned therein and normally standing adjacent the discharge end of said receptacle when the same is filled with the liquid, the liquid being held between said piston and the opposite or handle end of the receptacle, a hollow piston rod connected at one end to said piston and provided with openings adjacent the piston through which the liquid passes from said receptacle, said piston rod extending through the opposite end of the receptacle and being provided exteriorly thereof with a handle by means of which the piston is moved from its normal position at the discharge end of the receptacle to the opposite end thereof and discharges the entire liquid contents by one stroke, regardless of the position in which the device is held, and a tube secured at one end to the discharge nozzle

and extending through the piston and interiorly of the hollow piston rod to the handle end thereof and providing therewith a passage for the liquid from the receptacle to the nozzle when the piston is moved from the discharge end to the opposite end of the receptacle, said air inlet admitting air from

the exterior thereof directly to the interior space in the receptacle and piston cylinder between the piston and discharge end 10 thereof.

Signed at city, county and State of New York, this 15th day of November, 1915.

ROBERT W. LEE.
